LEAD SIGHT FOR SHOTGUNS

Thomas F. Prather, Wasco, Calif.

Application March 13, 1937, Serial No. 130,771

1 Claim. (Cl. 33—51)

This invention relates to sights for shotguns. The primary object of the invention is to provide a front sight on a shotgun for use with a single rear peep sight wherein the target, such as a flying duck passing horizontally across the path of the vision may be led by the marksman at the time he fires the gun.

Another feature of the invention is to provide the front sight with an opening which when aligned with the rear sight opening is of a size that indicates the effective killing range of the gun when the target fits conformably across the diameter of the sight.

Further objects of the invention are to provide a sight of the character referred to that provides adjustment for the front sight, that is designed to permit efficient and inexpensive attachment to the muzzle end of the gun, that is very easy to operate and comparatively inexpensive to manufacture.

With the foregoing and other objects in view the invention consists of a novel construction, combination and arrangement of parts as will be hereinafter more specifically described and illustrated in the accompanying drawing wherein is disclosed an embodiment of the invention but it is to be understood that changes, variations, and modifications may be resorted to without departing from the spirit of the claim hereunto appended.

In the drawing wherein like reference characters indicate like parts throughout the several views:—

Figure 1 is a fragmentary top plan view of a gun provided with the invention.

Figure 2 is a rear elevation of the sight removed from the gun.

Figure 3 is a top plan view of Figure 2.

Figure 4 is an exploded view of the sight arms removed from assembled relation.

Figure 5 is a detailed vertical section taken substantially on the plane of line 6—6 of Figure 2.

In the drawing is shown a shotgun of conventional construction and numeral 1 indicates a single barrel which is mounted in the customary breech block which breech block is mounted on the usual stock. On the top of the breech block 2 I mount a conventional peep sight 4 and this peep sight may be of regulation construction. A peep sight as herein described is to be distinguished from open sights by the fact that all peep sights are to be constructed with a round aperture for sighting purposes.

The front sight is indicated at A and is formed with a split supporting ring 5 of metal having a

diameter to slip over and clamp to the muzzle end of a single barrel 1 of the shotgun. When assembled, the ring 5 fits snugly in tight immovable relation just rearwardly of the muzzle end of the gun as shown in Figure 1 of the drawing. A sleeve 6 is fixed in any suitable manner to the periphery of the ring and there is an opening extending through the sleeve indicated at 7. The center line of the opening extends transversely to the barrel and parallel to the cross flight of the target. A set screw 8 is mounted in a threaded opening 9 in the top wall of the sleeve having the inner end thereof extending into the opening 7. As will hereafter appear this set screw is provided to lock the sight arms in adjusted position.

The front sight A further includes a pair of aligning members indicated at B and C. One of the aligning members B is provided with a pair of spaced parallel arms 10, 11 and the other aligning member C is formed with a single arm 12 which fits snugly but slidably between the arms 10, 11 in the assembled relation. It will therefore be seen that in the assembled relation that the confronting arms on the members B and C overlap each other. The confronting ends of the arms on aligning members B and C fit snugly in the sleeve opening 7 and are of a width to slidably bear on the side walls of the opening. In the assembled relation the inner end of the set screw 8 clamps against the overlapped arms and locks them in adjusted position.

On the outer free ends of arms 10, 11 is fixed in any suitable manner a ring member 13 having a central opening 14. Near the outer end of arm 12 is an enlargement 14a providing a shoulder 15 above and below the arm which provides a stop or abutment for the inner ends of the arms 10, 11. The enlargement 14a is fixed in any suitable manner to a ring member 16 provided with a circular opening 17.

In the assembled relation the circular opening in the rear peep sight 4 is along the center line of the barrel 1. When the ring 5 is mounted on the muzzle end of the barrel the sleeve 6 is set on the center line of the barrel also. With the inner ends of the arms on the aligning members B and C arranged in the sleeve opening 7 the centers of the respective openings 14, 17 will be disposed laterally, one on each side of the center line of the barrel. The round aperture in the peep sight 4 and the round openings 14, 17 in the front sight are selected so that their diameters will coincide when trained on a duck flying trans-

versely across the vision at the killing range of the gun which under ordinary circumstances is forty yards. The diameters of the openings in the front and rear sights are also selected so that when the length of the body of a duck conforms with the transverse diameter of the aligned sights the marksman will be apprised that the duck is within killing range. On the other hand, if the body of the duck is smaller than the diameter of the sight when the front and rear sights are in alignment the marksman will know that the duck is out of killing range. With the rear peep sight being disposed along the center line of the barrel a duck flying transversely across the line of vision is sighted through the righthand aligning member C and due to the angular disposition of the barrel relative to the aligned sights the killing load will lead the flying duck sufficiently to compensate for the speed of travel. A duck approaching from the left will be sighted through the lefthand aligning member B. The feature of adjustability in the aligning members B and C relative to the center line of the barrel allows adjustment of the aligning members to compensate for variations in shooting conditions such as deflecting force of the wind, choke of the barrel and other factors of a similar nature. It is also within the contemplation of the present invention to change the peep sight for an aligning member B and C for different moving targets whose bodies when moving vary in length. It will also be seen in Figure 1 of the drawing

that the dotted line 18 indicates the line of vision when sighting an object approaching from the right which line passes through rear peep sight 4 and the righthand aligning member B. Dotted line 19 indicates the aiming line through the rear peep sight and the lefthand aligning member B.

It will thus be seen that I have devised a front sight for attachment to a single barrel shotgun which particularly cooperates with a rear peep sight that not only provides an adjustable field for obtaining the proper lead on a cross flying object but also furnishes an effective killing range when the pattern of the object conforms with the aligned circular openings on the sights.

Having thus described my invention, what is claimed as new is:—

A front sight for a gun, comprising a member for connection with the muzzle end of the gun, a sleeve connected with the member and extending upwardly therefrom and having a transverse opening passing therethrough and a threaded opening extending from the upper end of the sleeve into the first mentioned opening, a pair of ring-shaped members, a pair of spaced parallel arms projecting from one ring-shaped member, a single arm projecting from the other ring-shaped member, said arms entering the transverse opening in the sleeve, with the single arm located between the pair of arms, and a clamping screw in the threaded opening for clamping the arms in the sleeve.

THOMAS F. PRATHER.
